Primary Examiner — Jennifer Rivard*(74) Attorney, Agent, or Firm* — ScienBiziP, P.C.(57) **CLAIM**

The ornamental design for a shaver, as shown and described.

DESCRIPTION

FIG. 1 is a front perspective view of a shaver showing my design.

FIG. 2 is a rear perspective view of the shaver.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front perspective view of the shaver wherein a main body and a cap of the shaver are taken apart.

FIG. 10 is a rear perspective view of the shaver wherein the main body and the cap of the shaver are taken apart; and, FIG. 11 is an enlarged view of a portion of the main body of the shaver labeled 11 in FIG. 9.

The broken lines in the drawings are employed to show unclaimed portions of the shaver, and form no part of the claimed design.

1 Claim, 11 Drawing Sheets(56)
